UNITED STATES PATENT OFFICE.

EDWIN L. PETERSON, OF PITTSBURGH, PENNSYLVANIA, ASSIGNOR, BY MESNE ASSIGNMENTS, TO SHARON PRERESSED STEEL COMPANY, OF PITTSBURGH, PENNSYLVANIA, A CORPORATION OF PENNSYLVANIA.

COUPLING FOR TRUCKS.

Application filed August 1, 1918, Serial No. 247,728. Renewed August 2, 1922. Serial No. 579,283.

To all whom it may concern:

Be it known that I, EDWIN L. PETERSON, a citizen of the United States, residing at Pittsburgh, in the county of Allegheny and State of Pennsylvania, have invented certain new and useful Improvements in Couplings for Trucks; and I do hereby declare the following to be a full, clear, and exact description of the invention, such as will enable 10 others skilled in the art to which it appertains to make and use the same.

My invention relates to trucks, but more particularly to couplers for trucks, or means for connecting two or more such vehicles together.

It has for an object the manufacture of couplers for the purpose indicated, which are highly efficient in operation, durable in construction, and economical of production.

20 A further object of this invention is the production of couplers having means whereby they are readily retained in a vertical position to economize storage space when not in actual service.

25 A further object is the production of means whereby such couplers are prevented from coming into contact with a floor or roadbed when carelessly or accidentally disconnected from a leading truck.

30 A further object is the production of couplers which are not likely to become accidentally uncoupled, but which at the same time may readily be detached when necessity or occasion requires.

35 With the foregoing and other objects in view the invention will now be particularly described and later pointed out by the claims following.

40 In the accompanying drawings which form part of this application for Letters Patent, and whereon like characters indicate corresponding parts in the several views:

Figure 1 illustrates mainly in plan the rear end of a leading or motor truck, and 45 the front end of a trailer connected by my improved coupler.

Figure 2 is a side elevation of parts illustrated by Figure 1, and

50 Figure 3 is a fragmentary view in side elevation showing the coupling link and means by which the coupler may be automatically retained in a vertical position when not in service.

Reference being had to the drawings and

55 numerals thereon, 1 indicates an advance or leading truck, and 2 indicates a trailer, both of ordinary or any approved construction, the latter equipped with a pair of eye-bolts or clevises 3, 3, one on either side of its center, and the former having a central rearwardly projecting coupling eye 4, but all securely attached to the frame of their respective trucks.

60 In the clevises 3, 3 of truck 2 are mounted the bifurcated ends of my improved coupler, as shown by Figure 1. This coupler may be made of any suitable material, but preferably of malleable iron, ribbed longitudinally as indicated at 5, for strengthening purposes, and preferably, but not necessarily, of bifurcated or V form, as shown.

65 At its free end this coupler is provided with an ordinary integral hook 6 adapted to enter the eye 4 as shown by Figures 1 and 2, for coupling purposes, its projecting bifurcated ends being provided with coupling shackles 7 of approximately triangular form having an opening or gap 8 in one side thereof. The opening 8 of these shackles 7 is upon the under side of each, and is of liberal 70 dimensions, as best shown by Figures 2 and 3, the shackles themselves upon both sides of their respective openings or gaps 8 being slightly inturned as shown at 9 for purposes which will appear in connection with 75 a brief statement of operation as follows:

Presuming the relation of parts to be as indicated by Figures 1 and 2, it is quite obvious that truck 2 will trail after truck 1 accurately, with little or no chance of becoming accidentally uncoupled. If, however, it is desired to disconnect the trucks

80 this is readily accomplished by merely lifting the hook member 6 out of its eye 4, whereupon it will assume substantially the 85 position indicated by dotted lines in Figure 2, but will not come in contact with the warehouse floor or ground this being prevented by engagement of the vertically positioned relatively straight side of the triangular 90 shackle 7 with the vertical surface provided in the clevis or eye 3, whereby the longitudinal axis of the improved coupler is maintained in approximately a horizontal position.

95 When, however, it is desired as a matter of economizing space in a warehouse, for example, or elsewhere, the outer free end of

the bifurcated coupling member may be lifted to a vertical position indicated by Figure 3 of the drawings where it will remain safely against the chance of accidental 5 dislodgement.

During the last operation the triangular shackles 7 merely slide through the openings of their respective clevises 3 until arrested as shown in Figure 3, by the upper 10 hooked inturned end 9, in which position the coupler will securely remain until manually dislodged. When, on the other hand, it is desired to couple one truck equipped 15 with my invention to another, the coupler is first lifted bodily and then turned upon its clevises 3, until its draw-hook 6 enters the coupling eye 4, upon the leading truck.

When lifted from said coupled position, as will be apparent by a glance at Figure 2, 20 the outer end of the coupler descends only partially because of engagement of the relatively straight side of the triangular shackle 7 with the vertical surface provided in the clevis or eye 3, where it is arrested as indicated by dotted lines in said Figure 2.

The form of coupler shown and described is its best form at present known to me, but at the same time it should be understood that various changes in the form, arrangement and combination of the component 30 parts of this device may readily be made and substituted for those herein shown, without in the least departing from the spirit of the invention, so long as the functions of coupling and of removably sustaining the coupler in a vertical or horizontal 35

position by means substantially such as shown is present.

Having thus described my invention, what I claim and desire to secure by Letters Patent is:

1. A coupler for trucks including a coupling shackle of approximately triangular form having one of its sides broken away with inturned ends forming hooks adapted 45 to loosely surround a suitable attaching clevis, and having extended outer bearing surfaces upon its remaining sides for selectively engaging the end sill of a truck.

2. A bifurcated coupler for trucks including coupling shackles of approximately triangular form each having one of its sides broken away with inturned ends forming hooks adapted to loosely surround suitable attaching clevises and having extended 55 outer bearing surfaces upon its remaining sides for selectively engaging the end sill of a truck.

3. A coupler for trucks including in combination a coupling shackle of triangular 60 form having a gap in one of its sides adapted to loosely surround a suitable attaching clevis and having extended outer bearing surfaces upon its remaining sides for selectively engaging the end sill of a truck. 65

In testimony whereof I affix my signature, in presence of two subscribing witnesses.

EDWIN L. PETERSON.
